[57] CLAIM

I claim the ornamental design a wall mounted music responsive color organ, substantially as shown and described.

DESCRIPTION

FIG. 1 is a front elevation of a wall mounted music-responsive color organ, showing my new design;
FIG. 2 is an end elevation view thereof;
FIG. 3 is a top plan view thereof;
FIG. 4 is a bottom plan view thereof;
FIG. 5 is a rear elevation thereof;
FIG. 6 is an end elevation as seen from the left of FIG. 1; and
FIG. 7 is a top front perspective thereof.

FIG. 2

FIG. 1

FIG. 3

FIG. 4

FIG. 7
